UNITED STATES PATENT OFFICE.

JOSEPH DESTRÉE, OF BRUSSELS, BELGIUM.

FIREARM.

Application filed November 23, 1926, Serial No. 150,853, and in Belgium November 27, 1925.

The present invention relates to automatic fire arms and to the obturating and percussion mechanism employed in conjunction with this cartridge.

5 The cartridge case constructed according to my invention has for its object to permit the engagement of an inwardly directed flange in an extension of the cartridge case by a hooking organ which is situated on 10 the obturating mechanism. The cartridge case is cylindrical and this form is necessary for permitting the case to recoil under pressure without distorting or tearing itself.

15 Cartridges have been known in which hooked extractors engage a flange in an extension of the base but they are conical and not cylindrical as is the case in the present invention.

20 The invention has also for its object an obturating device permitting the employment of this cartridge in an automatic fire arm.

25 This device comprises an obturator provided with an extension engaging with an extension of the barrel, and presenting a part capable of engaging with the recess of the case base herebefore specified and a firing pin provided with a hooking lip capable of engaging outside the said part. As this 30 hooking lip may be constituted by a portion of a ring of a rather great length, the said part of the obturator engaging with the recess of the case base may press on the whole surface of the cap.

35 The invention has also provided for a percussion device comprising a hooking member which can extract the case of the cartridge fired.

40 The accompanying drawings show by way of example several constructions according to the invention. In the said drawings,

Figure 1 is a section through a cartridge case.

45 Figure 2 is a similar section through a modified construction.

Figure 3 is a section through the end of an obturator.

50 Figure 4 shows in perspective view another obturator as well as the upper edge of a cartridge magazine which can be utilized in the same arm.

55 Figure 5 is a longitudinal section through the rear portion of the barrel of the said arm, the obturator being in the closing position.

Figure 6 is a similar section to that of Figure 3, through a modified construction.

Figure 7 shows in perspective an obturator with a special construction of the extraction lip.

60 Figure 8 is a section of the cartridge to be used in a fire arm provided with the obturator according to Figure 7.

The base of the cartridge case, shown in Figures 1 and 2, is extended at 1 beyond the 65 cap 2 to be fired, and has in its rear portion a recess 3 enabling the firing pin to reach the said cap. The said recess comprises towards the interior a flange 4 enabling the case to be hooked or seized by an extractor introduced into the said recess. In the case of Figure 1, the extension 1 is sufficiently 70 strong to withstand the whole or part of the reactions which the case transmits to the obturator during the firing. In the case of Figure 2, these reactions will be transmitted directly by the bottom of the recess 3, and the extension will be exposed only to 75 tensional stresses, and only during the extraction of the case.

80 Figure 3 shows an obturator 5 which could be used in co-operation with a cartridge case such as those just described. This obturator is provided with an extractor 6 which is elastically connected to it, owing to the fact 85 that it is made as a flexible part, the lip of which is directed outwards, that is to say, towards the periphery of the barrel. During the closing of the arm, this extractor engages with the recess 3 of the cartridge 90 case, and the lip engages behind the flange 4 in such a manner that when the arm is opened, the case shall be extracted.

95 Figures 4 and 5 relate to an arm in which the use of a cartridge case built in accordance with Figure 1 and in the manner just described, is particularly advantageous.

In the said arm, the obturator 5 comprises an extension 7 which, during the closing, engages with an extension 8 of the barrel 9. 100 Owing to this arrangement, during the recoil of the obturator relatively to the barrel, the chamber of the latter remains closed as long as the two extensions are not separated from each other.

105 The extension 7 of the obturator comprises a part 10 which can engage with the recess 3 of a case such as that shown in Figure 1.

The firing pin 11 which is mounted in the obturator, comprises a hooking lip 12 ca-

pable of projecting out of the part 10 and of engaging with the flange of the case.

The percussion is produced by means of a hammer 20 when the hooked notch 14 is disengaged from the trigger not shown and built in any desired well known manner. The percussion is produced by the point of the firing pin which strikes the cap contained in the base of the case.

10 When the obturator begins to make a recoil movement relatively to the barrel 9, the firing pin provided with its extraction lip 12, will be moved laterally (that is to say, upwards in the case of Figures 4 and 5), by 15 the action of a spring 21 mounted in the obturator.

During the firing or percussion, the firing pin somewhat compresses the said spring 21 owing to the action of the conical wall of 20 the recess 3.

When the lip 12 has been moved laterally, it engages behind the flange 4, and hooks the latter. The projecting portion 16 of the shank of the firing pin is at this moment 25 driven rearwards by a flange 17 which is provided in the obturator and with which engages a return spring 22 of the firing pin, arranged between the said flange 17 and the projecting portion 16.

30 The firing pin and its hooking lip 12 are thus driven rearwards by the said obturator 5, and thus bring about the extraction of the case; the latter will be ejected upwards when its rear face comes in contact with the ejectors 18 secured to the magazine 19 shown in Figure 3.

In the construction shown in the drawings, the obturator 5 is provided at its lower portion at 23 with a reduced portion capable 40 of engaging between the lips of the magazine 19. When the obturator has recoiled sufficiently a cartridge is pushed past from the magazine. When the obturator closes up again the free end of the part 10 of the 45 prolongation 7 of the obturator pushes the cartridge before it with a sliding action in orthodox fashion into the back part and interior of the weapon.

The modified construction shown in Figure 6, differs from the preceding construction by its percussion device.

The percussion or firing is produced by means of a percussion spring 13 when the hooked notch 14 of the striker or firing pin 55 is disengaged from the trigger not shown. As regards the lateral movement, it is obtained by the co-operation of ramps or cams 24 and 15, one of which 24, forms part of the obturator, and the other, 15, of the 60 striker. When the cartridge is fired the gas drives back the case and in consequence of the obturator engaging it at the given moment, the case is stopped by the ejectors 18 but the obturator is caused to recoil un- 65 interruptedly by its own inertia. In these

conditions the percussion spring 13 achieving the release which has been checked by the contact of the percussion means with the cap is brought into contact with the obturator. By means of the relative movement 70 which is thus produced between the percussion means and the obturator the inclined planes 15 and 24 compel the former to displace itself laterally and the hooking organ 12 is caused to catch the lip or flange 4 75 of the cartridge.

As in the case of Figure 6, it is no longer necessary to use a return spring of the firing pin, the parts 16 and 17 could come into direct contact.

80 Figure 7 shows an obturator of the kind shown in Figure 6, but its hooking lip 12 has the shape of a portion of a ring hooking the flange 4 along a great length, whilst at the same time enabling the end face of the 85 part 10 to press on the whole surface of the cap 2. In this way, the latter cannot become deformed during the explosion.

The elongated shape of the lip 12 makes it also possible, for one and the same effort of 90 extraction of the case, to reduce the dimension of the lip in the direction of the axis of the case.

This peculiarity makes it possible to reduce proportionately the depth of the recess 95 3 (Figure 8) which results in a saving of material and in facilitating the machining.

What I claim is:

1. A percussion device for fire arms comprising a firing pin, an extraction lip secured to the firing pin, means for laterally displacing the firing pin after the percussion.

100 2. A percussion device for fire arms comprising a firing pin, an extraction lip secured to the firing pin, a spring for laterally displacing the firing pin after the percussion.

105 3. A percussion device for fire arms comprising a firing pin, an extraction lip secured to the firing pin, ramps for laterally displacing the firing pin after the percussion.

110 4. An obturation device for fire arms comprising an obturator with an extension engaging with an extension of the barrel, a 115 part capable of engaging with the recess of a case base of the character described arranged on said extension, a firing pin provided with a hooking lip capable of projecting outside the said part.

120 5. An obturation device for fire arms comprising an obturator with an extension engaging with an extension of the barrel, a part capable of engaging with the recess of a case base of the character described arranged on said extension and capable of pressing on the whole surface of the cap, a 125 firing pin provided with a hooking lip capable of projecting outside the said part.

130 6. An obturation device for automatic fire

arms comprising an obturator with an extension engaging with an extension of the barrel, a part capable of engaging with the recess of a case base of the character described arranged on said extension, a firing pin provided with a hooking lip capable of projecting outside the said part.

7. An obturation device for automatic fire arms comprising an obturator with an extension engaging with an extension of the barrel, a part capable of engaging with the recess of a case base of the character described arranged on said extension and capable of pressing on the whole surface of the cap, a firing pin provided with a hooking lip capable of projecting outside the said part.

8. A percussion device for automatic fire arms comprising a firing pin, an extraction lip secured to the firing pin, means for laterally displacing the firing pin after the percussion. 25

9. A percussion device for automatic fire arms comprising a firing pin, an extraction lip secured to the firing pin, a spring for laterally displacing the firing pin after the percussion. 30

10. A percussion device for automatic fire arms comprising a firing pin, an extraction lip secured to the firing pin, ramps for laterally displacing the firing pin after the percussion. 35

In testimony whereof I affix my signature.
JOSEPH DESTRÉE.
